COKE OVEN BATTERY

Walter Staekel, Bochum, Germany, assignor, by
mesne assignments, to Fuel Refining Corpora-
tion, a corporation of Delaware

Application August 7, 1937, Serial No. 157,873
In Germany September 5, 1936

2 Claims. (CL 202—144)

It has been observed that in externally heated coke ovens in which the fuel charge is introduced through a plurality of apertures in the oven cover which are distributed over the length of the 5 chamber, although uniform heating of the two longitudinal walls of the chamber is arranged the part of the charge located between the charging apertures, particularly towards the top of the charge was carbonised more slowly than the rest 10 of the charge. It appears that this phenomenon may be explained as follows: the coal which passes through the charging apertures forms a conical heap down the sloping sides of which the coal slides; in consequence of this a grading of 15 the coal into different sizes takes place with the finer grades located, more or less directly under the charging apertures and the coarser grades disposed towards the sides of the apertures.

The subject of the invention is a coke oven battery 20 having intermediate heating chambers, which are divided into vertical flues, the heating flues being arranged to be supplied with fuel in groups, in such a manner that the groups of heating flues which are arranged at the side of a part 25 of an oven chamber which is located below a charging aperture, can be provided with fuel in such manner that the rate of heating therein is different from the rate of heating in the group or groups of heating flues arranged at the side 30 of the remaining parts of the oven chamber. In this manner it is possible for the parts not located under the charging apertures to be heated more intensively than the remaining parts and thus for allowance to be made for the fact that 35 the coarser grades of coal are inferior in thermal conductivity as compared with the finer grades of coal.

In an embodiment of the invention the heating walls are divided into twin flues, the arrangement being such that each part of the chamber located below a charging aperture corresponds to a pair of twin flues, and each of the remaining parts of the chamber corresponds to one or more other pairs of twin flues. In this arrangement 45 the axis of each charging aperture may be located in the plane of the prolongation of the flue division wall which separates the two flues of a pair of twin flues.

With the type of oven having vertical heating flues, in which in some or all of the flues there 50 are provided burners for supplying rich gas which project above the heating flue sole; those burners in the heating flues which are arranged at the side of the part of the chamber which is located 55 below a charging aperture are arranged to be

lower than those in the heating flues which are at the side of the remaining parts of the oven chamber; thus in the last named flues the rich gas flame can be placed higher and therefore the formation of badly coked portions in the upper part of the charge between the charging apertures is avoided.

In twin heating flues having a higher burner in one heating flue of each pair and a lower burner in the other, the burners of both kinds which 10 are disposed at the side of parts of the oven chambers which are not below the charging apertures are higher than the corresponding burners in the pairs of twin flues located at the side of 15 the parts of the oven chambers which are below the charging apertures.

For lean gas heating it is advisable to enlarge the passages between the air and lean gas regenerators and those heating flues which must be 20 more strongly heated. Arrangements are known for mixing air and lean gas intimately at the bottom of the heating flues. Such apparatus for mixing lean gas and air consist preferably of outlet channels for lean gas and air disposed angularly in respect of one another in the heating flue, the air and gas being caused to mix with each other in swirling currents, or consist of deflecting surfaces placed in the path of the issuing gas and air. These apparatus, in the flues located at the 25 side of the chamber parts below the charging holes may, to carry out the invention, have a weaker mixing action or be entirely omitted in order thus to lengthen the lean gas flame and extend it upwards. For example, the outlet channels for lean gas and air may converge at a more 30 acute angle or the deflecting surfaces may be arranged less inclined.

In the accompanying drawing which illustrates 35 by way of example a chamber oven embodying the invention:

Fig. 1 is a vertical section in the longitudinal direction through a heating wall and, in the left-hand upper corner of the figure through an oven chamber.

Fig. 2 is a vertical section in the longitudinal direction of the battery along the line II—II of Fig. 1, and

Fig. 3 is a similar section along the line III—III of Fig. 1.

The oven chambers *a* separated by intermediate heating walls, are charged with fuel through charging apertures *b*. Below the chambers there are arranged regenerators combined in groups of three, of which in one operative period the middle one *c* serves for pre-heating lean gas, and the 55

two outer ones *d* for pre-heating air, while in the other operative period all three regenerators conduct waste gases. The supply of rich gas is effected by distributing pipes *e* and *f* arranged in 5 the cellar like space shown, and vertical channels *g*.

The arrangement of the charging apertures and sub-division of the heating wall into twin flues is carried out in such manner that at the 10 side of each part of the oven chamber which is located below a charging aperture there is a pair of twin flues *h*, while at the side of the remaining parts of the chamber there are arranged pairs of twin flues *i*. As shown, the two flues *h* collectively forming a hairpin flue alongside each oven 15 chamber portion immediately beneath a charging opening *b*, are at opposite sides of the vertical plane transverse to the length of the coking chamber and passing centrally through said 20 opening. As each individual heating flue is connected in a regulable manner with one of the two rich gas pipes *e* and *f*, a greater quantity of rich gas can be supplied forthwith to the heating flues located at the side of those parts of the 25 chamber which are not below the charging apertures. The burner heads *k* which are arranged in pairs of high and low burners, and to which the channels *g* open, are higher in the flues *i* than in the flues *h* so that it is possible to arrange 30 the rich gas flame higher in those flues. Thus, the average rich gas burner level is higher in the flues *i* than in the flues *h*, and the ratio of fuel burnt in the upper portion of the flues to fuel burnt in the lower portion of the flue, is made 35 lower in the case of the flues *h* than in the case of the flues *i*.

The ratio of top heating effect to bottom heating effect of the flues *i*, may be made greater than that of the flues *h*, in operation with lean fuel 40 gas, by the arrangement of the air and gas mixing means associated with the lower portions of the flues, so as to obtain more effective mixing action in the lower portions of the flues *h* than in

the lower portions of the flues *i*. The passages *m* and *n* to the generators *c* and *d* have, in the case of the heating flues *i* a greater cross section than in the case of the heating flues *h*. These differences in the heating of the flues located at the 5 side of the oven chamber parts which are below the charging apertures and the remaining flues, render it possible for the entire contents of the chamber to be caused to carbonise more uniformly than has been the case heretofore. 10

What I claim and desire to secure by Letters Patent is:

1. A coke oven battery having a horizontally elongated oven chamber and spaced apart charging openings in the top wall of said chamber, a heating wall alongside said chamber and formed with vertical heating flues arranged in groups respectively adjacent the portions of the oven chamber immediately beneath the charging openings and in other groups respectively adjacent the portions of the oven chamber at the sides of the first mentioned portions, and combustible agent supply means associated with the different groups of flues and comprising burners opening to said flues at a level which averages lower in flues of 25 the first mentioned groups than in flues of said other groups.

2. A coke oven battery having a horizontally elongated oven chamber and spaced apart charging openings in the top of said chamber, a heating wall alongside said chamber and formed with vertical heating flues arranged in groups respectively adjacent the portions of the oven chamber immediately beneath the charging openings and in other groups respectively adjacent the portions 30 of the oven chamber at the sides of the first mentioned portions, and combustible agent supply means associated with the different groups of flues and comprising regenerator connections to the lower ends of said flues which are of smaller 35 cross sections for flues of the first groups than for flues of the other groups.

WALTER STAECHEL.
